RAILWAY SIGNALING

Earl M. Allen, Swissvale, Pa., assignor to The Union Switch & Signal Company, Swissvale, Pa., a corporation of Pennsylvania

Application May 28, 1932, Serial No. 614,198
Renewed October 21, 1933

12 Claims. (Cl. 246—3)

My invention relates to railway signaling, and particularly to railway signaling for stretches of single track over which traffic moves in both directions.

5 A feature of my invention resides in the provision, in signaling of the type here involved, of novel and improved means controlled, in part at least, from a remote despatcher's office or tower, for routing traffic over a stretch of railway track 10 in either direction. In reverse signaling systems heretofore proposed it has been customary to provide a double line wire traffic locking circuit that extends the entire length of the protected stretch 15 of railway. In my improved arrangement a traffic locking circuit is provided, one wire of which is the common line wire of the usual automatic signal system, and repeater equipment is provided to bridge the points where the common line wire is sectionalized, with the result that one less 20 line wire is required. Other features of my invention will appear as the specification progresses.

I will describe one form and arrangement of apparatus for railway signaling embodying my invention, and will then point out the novel features thereof in claims.

In the accompanying drawings, Figs. 1^a and 1^b, when placed end to end with Fig. 1^a at the left, are a diagrammatic view of one form of apparatus for railway signaling embodying my invention when applied to the usual automatic signal system for a stretch of railway over which traffic moves in both directions.

Referring to Figs. 1^a and 1^b, the traffic rails 1 and 1^a of a stretch of railway track, extending 35 between two locations designated by the reference characters X and Y, are divided by the usual insulated rail joints to form a plurality of track sections 1T, 2T, 3T, 4T, 5T and 6T. Each track section is provided with the usual track circuit 40 consisting of a source of current such as a battery 7, and a track relay designated by the reference character TR plus a numeral corresponding 45 to the section. In the accompanying drawings each of these track relays is shown conventionally by a dash line connected to the track rails of the section at the end opposite the battery.

This stretch of railway is provided with an automatic signal system which includes signals 2, 4 and 6 for governing eastbound traffic, that is, traffic moving from the left to the right in the drawings, and signals 3, 5 and 9 for governing westbound traffic, that is, traffic moving from the right to the left in the drawings. In accordance with standard practice there is associated with the signal system for the stretch of

railway between the locations X and Y a sectionalized common line wire, the three sections of which are designated by the reference characters CL1, CL2 and CL3, respectively. That is to say, the common line wire for the usual automatic signal system for the railway extending between locations X and Y is sectionalized at opposing intermediate signal locations 2—3 and 4—5. The circuits for the automatic signals form no part of my invention and so are omitted from the drawings for the sake of simplicity. While a specific arrangement of track sections and signals is disclosed, it will be understood that my invention is not limited to this specific arrangement. The significant point, as far as my invention is concerned, is the fact that the common line wire for the automatic signal system is sectionalized at the opposing intermediate signal locations.

Eastbound traffic entering this stretch of railway is governed by a signal R2, and westbound traffic entering the stretch is governed by a signal L1. These signals R2 and L1 are included in the automatic signal system, and are also controlled by two remote controlled relays R2HS and L1HS, respectively. The means for governing the remote controlled relays R2HS and L1HS is not shown in the drawings as it forms no part of my invention. Suffice it to say, that the means may be a centralized traffic control system, a remote control system or a local circuit governed by a manually operated lever located in a nearby tower. As a matter of fact one such means may be used to control one relay and a dissimilar means used to control the other relay should it seem desirable to do so.

Associated with the remote controlled relay R2HS are a directional relay R2FR, a directional stick relay R2SR, and signal controlling relay R2H. At location Y a similar layout of relays, including a directional relay L1FR, a directional stick relay L1SR, and a signal controlling relay L1H, is associated with the remote controlled relay L1HS.

As will appear hereinafter, these relays located at the locations X and Y govern traffic in opposite directions through the stretch in such a manner as to permit trains to follow each other through the stretch but to prevent two opposing trains from occupying the stretch at the same time. Cooperation between the relays at the two locations is obtained by a traffic locking circuit extending between the two points, and which includes the sections of the common line wire as will be described in detail as the specification progresses. At each point where the common

line wire is sectionalized, repeater equipment is provided for the traffic locking circuit, which equipment includes an eastbound directional relay and a westbound directional relay at each repeater location. At intermediate signal location 2-3 there is provided repeater equipment which includes an eastbound directional relay 2FR and a westbound directional relay 3FR. Likewise, at signal location 4-5 the repeater equipment includes an eastbound directional relay 4FR and a westbound directional relay 5FR. Although in the drawings only two repeater locations are shown, it will be understood that the common line wire for the usual signal system may be sectionalized at any number of locations with repeater equipment provided at each location, each such equipment being a duplication of that shown at each of the signal locations 2-3 and 4-5.

As shown in the drawings the westbound directional relay 3FR at signal location 2-3 is retained energized by supplying the traffic locking circuit with current from a battery 10 placed at location X. This section of the traffic locking circuit extends from battery 10, through circuit controller 11 operated by the signal R2 and closed only when that signal indicates stop, back contact 12 of the directional relay R2FR, back contact 13 of the directional stick relay R2SR, back contact 14 of the remote controlled relay R2HS, front contact 15 of track relay 1TR for track section 1T, line wire TL1, front contact 17 of track relay 2TR, back contact 18 of relay 2FR, winding of relay 3FR and thence by the section CL1 of the common line wire to the opposite terminal of battery 10. The energizing of westbound directional relay 3FR repeats the traffic locking circuit east from location 2-3 by causing current to be supplied from battery 19 at that location to the westbound directional relay 5FR at the next intermediate signal location 4-5. This section of the traffic locking circuit is from positive terminal of battery 19, through back contact 20 of relay 2FR, front contact 21 of relay 3FR, front contact 22 of track relay 3TR, line wire TL2, front contact 23 of track relay 4TR, back contact 24 of directional relay 4FR, winding of relay 5FR and thence by the section CL2 of the common line wire to the negative terminal of battery 19. The energizing of the westbound directional relay 5FR at location 4-5 repeats the traffic locking circuit by causing the positive terminal of battery 25 at location 4-5 to be connected to the section of the traffic locking circuit leading east from that point to location Y. This section of the traffic locking circuit extends from the positive terminal of battery 25 through back contact 26 of relay 4FR, front contact 27 of relay 5FR, front contact 28 of track relay 5TR, line wire TL3, front contact 29 of track relay 6TR, back contact 30 of the remote controlled relay L1HS, back contact 31 of directional stick relay L1SR, back contact 32 of directional relay L1FR, and thence to the positive terminal of a battery 34 at location Y through a circuit controller 33 of signal L1 closed only when that signal is at stop. The negative terminal of battery 34 is connected to the section CL3 of the common line wire as is also the negative terminal of the battery 25, and thus it follows that normally no current flows in this section of the traffic locking circuit just traced, the voltage of battery 34 opposing the voltage of battery 25, it being understood that these batteries are of substantially equal voltage.

Thus, with the apparatus as shown in the draw-

ings, current is supplied by battery 10 at the west end of the stretch of railway over one section of the traffic locking circuit to the repeater equipment at the location 2-3, causing the westbound directional relay at that location to be energized. Energizing the westbound directional relay 3FR at this first repeater location causes its battery 19 to be connected to the next section of the traffic locking circuit for energizing the westbound directional relay at the next repeater location which in this instance is the location 4-5. Energizing the westbound directional relay 5FR at the second repeater location causes the battery 25 at that location to be connected to the next section of the traffic locking circuit which in this instance leads to the location Y. Normally no current flows in this last section of the traffic locking circuit as the batteries 25 and 34 at the opposite ends of the section are both connected to the traffic locking circuit and the voltage of one battery opposes that of the other.

To establish westbound traffic from location Y the despatcher will energize the remote controlled relay L1HS, leaving the remote controlled relay R2HS at the location X deenergized. In the event these two relays are to be controlled by different operators then the two operators must so cooperate that relay L1HS is energized and relay R2HS remains deenergized. Energizing relay L1HS transfers the connection of the traffic locking circuit from battery 34 to one terminal of the winding of the directional relay L1FR by opening its back contact 30 and closing its front contact 35. The opposite terminal of the winding of relay L1FR being permanently connected to the common line wire section CL3, that relay is now energized by current supplied by battery 25 at location 4-5, it being understood, that the apparatus is in the condition shown in the drawings with all track relays of the stretch picked up. Both relay L1HS and relay L1FR being now energized, a circuit for the signal controlling relay L1H is completed to energize that relay. This control circuit for the signal controlling relay L1H may be similar to that employed for controlling all signals of the automatic signal system with which this stretch of railway track is provided, and in this instance it is shown as a polarized line circuit, the relay L1H being of the polarized type. To be explicit, the control circuit for relay L1H passes from the positive terminal B of a convenient source of current at the next signal 5 in advance, through pole-changing contact 42 operated by signal 5, front contact 54 of track relay 5TR, front contact 37 of track relay 6TR, winding of relay L1H, back contact 38 of directional stick relay L1SR, front contact 39 of directional relay L1FR, front contact 40 of remote controlled relay L1HS, front contacts 41 and 55 of relays 6TR and 5TR, respectively, and pole-changing contact 36 of signal 5 to the negative terminal C of the same source of current. With signal 5 occupying either the clear or caution position the pole-changing contacts 36 and 42 occupy the positions shown by the solid lines in the drawings and relay L1H is energized with current of normal polarity, causing its two neutral front contacts 43 and 44 to be closed and its polar armature 45 to be held in the left-hand position. If signal 5 occupies its stop position, pole-changing contacts 36 and 42 are shifted to the positions shown by the dotted lines in the drawings, and relay L1H is then energized with current of reverse polarity causing its front contacts 43 and 44 to be closed as before and its polar armature 45 to be shifted

- to the right-hand position. When relay L1H is energized with current of normal polarity an operating circuit which includes the wires 46 and 47 leading to the signal L1 is closed, and that signal is then operated to its clear position. With relay L1H energized with current of reverse polarity the operating circuit to signal L1 includes the wires 46 and 48 and the signal is operated to its caution position.
- Assuming that the signal L1 has been cleared in the manner just described, and a westbound train advances past signal L1 into the track section 6T and shunts the track relay 6TR to open the front contact 29 included in the traffic locking circuit, the directional relay L1FR is de-energized. During the release period of relay L1FR a pick-up circuit for the directional stick relay L1SR is closed. This pick-up circuit is from the positive terminal B of a convenient source of current, through back contact 49 of track relay 6TR, front contact 50 of relay L1FR and winding of relay L1SR to the negative terminal C of the current source. Once picked up, relay L1SR is retained energized by its stick circuit that includes its own front contact 51 and the back contact 52 of relay L1FR, as will be readily understood by an inspection of the drawings. With directional stick relay L1SR thus energized to close its front contact 53, a branch path for the control circuit of relay L1H is closed around the front contact 39 of the directional relay L1FR. It follows that relay L1H will be reenergized and the signal L1 again cleared automatically as soon as this first westbound train vacates the two track sections 6T and 5T even though directional relay L1FR remains deenergized.
- When the westbound train passes signal 5 to enter the track section 4T, the opening of the front contact 23 of track relay 4TR opens the traffic locking circuit for directional relay 5FR, and that relay becomes deenergized. The opening of the front contact 27 of relay 5FR removes battery 25 from the section of the traffic locking circuit leading east from location 4-5, causing the directional relay L1FR to remain deenergized even after the train has vacated the track sections 6T and 5T. The westbound train, on passing the next westbound signal 3 and entering the track section 2T, will open the traffic locking circuit leading to the directional relay 3FR by shunting track relay 2TR, and thus will cause relay 3FR to be deenergized. The deenergizing of relay 3FR removes battery 19 from the section of the traffic locking circuit leading to the repeater location 4-5, causing directional relay 5FR to remain deenergized even after the train has vacated the sections 4T and 3T, and thus in turn holding the directional relay L1FR at location Y deenergized. Hence, the directional relay L1FR is continuously held deenergized as long as a train occupies any one of the track sections between the two locations X and Y. The signal controlling relay L1H is reenergized, however, whenever the track sections 6T and 7T become vacated, and signal L1 is then cleared for following trains in accordance with the usual operation of the automatic signal system. It is to be noted that the dispatcher retains control over the signal L1 and he can set signal L1 at stop or clear the signal by either deenergizing or energizing relay L1HS. The operation of relay L1HS, however, will not affect the directional selection, because the directional stick relay L1SR is retained energized by its stick circuit as long as the directional relay L1FR remains deenergized.
- When the last westbound train vacates the section 1T, the west section of the traffic locking circuit is closed causing the directional relay 3FR at the repeater location 2-3 to be reenergized. Relay 3FR connects battery 19 to the next section of the traffic locking circuit, and the directional relay 5FR at repeater location 4-5 is reenergized. Relay 5FR, on being picked up, closes, in turn, the section of the traffic locking circuit to the location Y and the directional relay L1FR is re-energized, restoring the directional stick relay L1SR to its normal deenergized position due to the opening of the back contact 52 in its stick circuit. It is to be noted that in the event the remote controlled relay L1HS has, in the meantime, been deenergized so that the connection to the directional relay L1FR is now open at the front contact 35, the traffic locking circuit is completed to the winding of relay L1FR through back contact 30 of relay L1HS and front contact 56 of directional stick relay L1SR, insuring thereby that relay L1FR will be reenergized as soon as the stretch of railway is vacated by the westbound trains even though the remote controlled relay L1HS has previously been deenergized.
- Again, assuming the parts of apparatus to occupy the positions shown in the drawings, the establishment of eastbound traffic from the location X is accomplished by proceeding as follows. The despatcher will energize the relay R2HS, leaving the relay L1HS at location Y deenergized. As relay R2HS picks up, the supply of current from battery 10 to the traffic locking circuit is removed by the opening of back contact 14 and westbound directional relay 3FR is deenergized. At the same time the traffic locking circuit is connected to one terminal of the winding of the directional relay R2FR by the closing of the front contact 57 of the relay R2HS. Deenergizing the westbound directional relay 3FR disconnects the battery 19 from the next section of the traffic locking circuit and the directional relay 5FR at the next repeater location is deenergized. De-energizing the relay 5FR, in turn, disconnects battery 25 from the section of the traffic locking circuit leading east from location 4-5. The apparatus at location Y being in its normal condition, current will now flow from battery 34 through circuit controller 33, back contact 32 of relay L1FR, back contact 31 of relay L1SR, back contact 30 of relay L1HS, front contacts 29 and 28 of track relays 6TR and 5TR, respectively, back contact 58 of relay 5FR, winding of east- bound directional relay 4FR and thence by the section CL3 of the common line wire to the negative terminal of battery 34. With eastbound directional relay 4FR picked up, current will be supplied to the section of the traffic locking circuit leading west from location 4-5, the path being from battery 59 through back contact 60 of relay 5FR, front contact 61 of the now en- ergized relay 4FR, front contacts 23 and 22 of track relays 4TR and 3TR, respectively, back contact 62 of relay 3FR, winding of eastbound directional relay 2FR and thence by the section CL2 of the common line wire to the negative terminal of battery 59. The energizing of the east- bound directional relay 2FR causes current to be supplied from battery 63 to the section of the traffic locking circuit leading west from location 2-3. This section of the traffic locking circuit is now from positive terminal of battery 63, through back contact 64 of relay 3FR, front con-

tact 65 of the now energized relay 2FR, front contacts 17 and 15 of track relays 2TR and 1TR, respectively, front contact 57 of relay R2HS, winding of directional relay R2FR and thence by 5 the section CL1 of the common line wire to the negative terminal of battery 63. It follows that the selecting of the remote controlled relay R2HS causes the westbound directional relay at each repeater location to be successively deenergized, 10 and then starting at the east end of the stretch each eastbound directional relay at the successive repeater locations is picked up if the track relays are picked up. The picking up of the directional relay R2FR at location X completes 15 the circuit for signal controlling relay R2H for clearing the signal R2. The control circuit for relay R2H is a polarized line circuit similar to the control circuit for the signal controlling relay L1H at location Y, and it is thought it will 20 be readily understood by an inspection of the drawings without further discussion.

Assuming the signal R2 has been cleared as the result of the despatcher energizing the relay R2HS, and assuming that an eastbound train has 25 entered the track section 1T shunting the track relay 1TR, the opening of the front contact 15 in the traffic locking circuit causes the directional relay R2FR to become deenergized. During the release period of relay R2FR a pick-up circuit 30 for the directional stick relay R2SR is closed after which that relay is retained energized by its stick circuit. The pick-up circuit for relay R2SR includes back contact 77 of track relay 1TR and front contact 78 of directional relay 35 R2FR, while the stick circuit for relay R2SR includes its own front contact 79 and the back contact 80 of relay R2FR. The eastbound train advancing past the signal 2 into the track section 3T shunts the track relay 3TR and opens the 40 traffic locking circuit at front contact 22, causing the eastbound directional relay 2FR to be de-energized. Relay 2FR, in turn, holds the circuit to the directional relay R2FR open at the front contact 65 even after the eastbound train has 45 vacated track sections 1T and 2T. The vacating of the track sections 1T and 2T by the eastbound train closes the control circuit to the relay R2H as the front contact 76 of directional stick relay R2SR is now closed, completing a branch path 50 around the now open front contact 70 of directional relay R2FR, and thus relay R2H is re-energized to clear signal R2 for following eastbound trains in accordance with the control of the automatic signal system. The despatcher, 55 however, still retains control over the signal R2 by the relay R2HS. As the first eastbound train advances past the signal 4 and shunts the track relay 5TR, the traffic locking circuit is opened at the front contact 28 and the eastbound direc- 60 tional relay 4FR is deenergized, removing battery 59 from the section of the traffic locking circuit leading west from location 4-5. It follows that the directional relay R2FR at location X is held deenergized as long as a train occupies 65 any one of the track sections, and the directional stick relay R2SR is retained energized by its stick circuit to maintain the direction of traffic. When the stretch of railway between X and Y becomes clear of eastbound traffic, the directional 70 relay 4FR is first reenergized, thereby applying current from battery 59 to the section of the traffic locking circuit leading west to the repeater location 2-3 to reenergize the eastbound directional relay 2FR. Relay 2FR, picking up, 75 in turn connects battery 63 to the section of the

traffic locking circuit leading to location X, causing directional relay R2FR to be reenergized and directional stick relay R2SR to be restored to its normal deenergized condition due to the subsequent opening of its stick circuit. Assuming 80 relay R2HS to have been retained energized until after the stretch is clear of all eastbound traffic and the directional stick relay R2SR has been deenergized, the deenergizing of the remote controlled relay R2HS by the despatcher will disconnect the directional relay R2FR from the traffic locking circuit and the apparatus will be returned to its normal condition except that now the eastbound directional relays 2FR and 4FR, at the repeater stations, are left energized in place 85 of the westbound directional relays 3FR and 5FR as shown in the drawings. In the event the remote controlled relay R2HS has been deenergized before the stretch is vacated by eastbound traffic, the connection to the directional relay R2FR is maintained through the back contact 14 of relay R2HS and the front contact 81 of the stick relay R2SR. Under this condition the directional relay R2FR will be first picked up, when the stretch is vacated, to open the stick 90 circuit for relay R2SR, and then as relay R2SR drops, the connection of the traffic locking circuit to relay R2FR will be opened at the front contact 81 and relay R2FR deenergized, with the result that the apparatus is restored to its normal 95 condition with the eastbound directional relays 2FR and 4FR left energized.

To establish either westbound traffic or eastbound traffic when the eastbound directional relays at the repeater stations are energized, the 100 despatcher will energize the proper remote controlled relay R2HS or L1HS as before. After the remote controlled relay has been energized the energizing of the associated directional relay by the traffic locking circuit will follow in a manner similar to that described hereinbefore. That is, the energizing of the corresponding directional relay will be effected if all track sections are unoccupied, in response to current applied to the traffic locking circuit at the far end of the 115 stretch.

To sum up, traffic is established in either direction through the stretch by first selecting the proper remote controlled relay. The associated directional relay is then energized by the traffic 120 locking circuit by starting at the far end of the stretch and picking up the corresponding directional relay at each repeater station in turn to thereby check that each track section is unoccupied. When the associated directional relay 125 is picked up, the corresponding signal is cleared in accordance with the usual control of the automatic signal system. The direction of traffic once thus established, trains can follow each other through the stretch as the direction of traffic is retained by the directional stick relay. The despatcher is free to operate either remote controlled relay, but he cannot effect a change in the directional selection as long as the stretch is occupied. As the last train vacates the stretch, the apparatus is automatically restored to its 130 normal condition. At each repeater station the directional relay corresponding to the direction of traffic last set up is left energized when the apparatus is restored to its normal condition. In the event the next directional selection made by the despatcher corresponds to that for which the directional relays at the repeater stations are left energized, the condition of the track relays 135 is at once checked by the traffic locking circuit. 145

- The repeater equipment at each repeater location acts to bridge the traffic locking circuit from one section of the circuit to the next. In the event the next directional selection made by the designer is opposite that corresponding to the energized directional relays at the repeater stations, these directional relays are successively de-energized and then starting at the far end of the stretch the corresponding directional relays are picked up to check the traffic condition of the track sections.
- Although I have herein shown and described only one form and arrangement of apparatus for railway signaling embodying my invention, it is understood that various changes and modifications may be made therein within the scope of the appended claims without departing from the spirit and scope of my invention.
- Having thus described my invention, what I claim is:
1. In combination, a stretch of railway track, signals located at intervals to govern traffic in one direction through the stretch, other signals located at intervals to govern traffic in the opposite direction through the stretch, a sectionalized line wire adapted for use as the common line wire in the control of said signals, a traffic locking circuit for the stretch having as one conductor the different sections of said sectionalized line wire, directional means at each end of the stretch to govern traffic entering the stretch at its end and each arranged to be at times controlled by the traffic locking circuit, a current source at each end of the stretch each adapted to at times supply current to the traffic locking circuit for controlling the directional means at the opposite end of the stretch, and repeating means including two directional relays at each sectionalized location of said line wire said relays being arranged to bridge the traffic locking circuit from one section of the line wire to the next section in either direction and thereby carry through from end to end of the stretch the control effected by the current source at one end to the directional means at the other end in either direction.
  2. In combination, a stretch of railway track, signals located at intervals to govern traffic in one direction through the stretch, other signals located at intervals to govern traffic in the opposite direction through the stretch, a sectionalized line wire adapted for use as the common line wire in the control of said signals, a traffic locking circuit for the stretch having as one conductor the different sections of said sectionalized line wire, directional means at each end of the stretch to govern traffic entering the stretch at its end and each arranged to be at times controlled by the traffic locking circuit, a current source at each end of the stretch each adapted to at times supply current to the traffic locking circuit for controlling the directional means at the opposite end of the stretch, and repeating means including two directional relays at each sectionalized location of said line wire and arranged to repeat the effect of the traffic locking circuit from one section of said line wire to the next in either direction and thereby carry through from end to end of the stretch the control effected by the current source at one end to the directional means at the other end in either direction.
  3. In combination, a stretch of railway track, signals located at intervals to govern traffic in one direction through the stretch, other signals located at intervals to govern traffic in the opposite direction through the stretch, a sectionalized line wire adapted for use as the common line wire in the control of said signals, a traffic locking circuit for the stretch having as one conductor the different sections of said sectionalized line wire, a current source and a relay at each end of the stretch, a manually controlled selector at each end adapted to include either the relay or the current source at its end in the traffic locking circuit, repeating means at each junction of adjacent sections of the traffic locking circuit including two directional relays controlled by the traffic locking circuit and arranged to repeat the effect of the traffic locking circuit from one section of the common line wire to the next in a direction corresponding to the direction from which said relays are controlled to carry through the influence effected by the applying of current to the traffic locking circuit at one end to the relay at the other end, a signal at each end of the stretch to govern the movement of traffic into the stretch, and means controlled by the relay at the same end of the stretch for clearing said signal.
  4. In combination, a stretch of railway track, signals located at intervals to govern traffic in one direction through the stretch, other signals located at intervals to govern traffic in the opposite direction through the stretch, a sectionalized line wire for the stretch adapted for use as the common line wire in the control of said signals, a traffic locking circuit for the stretch arranged into a plurality of sections each section of which includes a corresponding section of said common line wire, a relay and a current source at each end of the stretch, a manually controlled selector at each end adapted to include either the relay or the current source at its end in the traffic locking circuit, repeating means at each junction of adjacent sections of the traffic locking circuit including two directional relays controlled by the traffic locking circuit and arranged to repeat the effect of the traffic locking circuit from one section to the next in the direction corresponding to that from which said relays are controlled to carry through the influence effected by applying current to the traffic locking circuit at either end of the stretch to the relay at the other end, a signal at each end of the stretch to govern the movement of traffic into the stretch, and means controlled by the relay at the same end of the stretch for clearing said signal.
  5. In combination, a stretch of railway track, signals located at intervals to govern traffic in one direction through the stretch, other signals located at intervals to govern traffic in the opposite direction through the stretch, a sectionalized line wire for the stretch adapted for use as the common line wire in the control of said signals, a traffic locking circuit for the stretch arranged into a plurality of sections each section of which includes a corresponding section of said common line wire, a relay and a current source at each end of the stretch, a manually controlled selector at each end adapted to include either the relay or the current source at its end in the traffic locking circuit, repeating means at each junction of adjacent sections of the traffic locking circuit including two directional relays controlled by the traffic locking circuit and arranged to supply current to either adjacent section in response to being controlled from the other adjacent section, to thereby carry through the influence effected by applying current to the traffic locking circuit at either end of the stretch to the relay at the other end, a signal at each end of the stretch to

govern the movement of traffic into the stretch, and means controlled by the relay at the same end of the stretch for clearing said signal.

6. In combination, a stretch of railway track, 5 signals located at intervals to govern traffic in one direction through the stretch, other signals located at intervals to govern traffic in the opposite direction through the stretch, a sectionalized line wire for the stretch adapted for use as the 10 common line wire in the control of said signals, a traffic locking circuit for the stretch arranged into a plurality of sections each section of which includes a corresponding section of said common line wire, means at each end of the stretch each 15 adapted to at times supply current to the traffic locking circuit, a relay at each end of the stretch each controlled by the traffic locking circuit and arranged when energized to permit traffic to enter the stretch, and two directional relays and 20 a current source at each junction of adjacent sections of the traffic locking circuit controlled by the traffic locking circuit and arranged to supply current to either adjacent section when controlled by current from the other adjacent section 25 to thereby supply current to the relay at either end of the stretch in response to current supplied to the traffic locking circuit at the end opposite that relay.

7. In combination, a stretch of railway track 30 arranged into track sections each of which is provided with the usual track circuit including a track relay, a traffic locking circuit extending along the stretch arranged into a plurality of different sections with each section including a 35 front contact of each track relay of the track sections adjacent that section of the traffic locking circuit, a source of current and a directional relay at each end of the stretch, manually controlled means at each end to include either the current source or the relay at its end in the traffic locking circuit, repeating means at each junction of adjacent sections of said traffic locking circuit including a current source and two directional relays controlled by the traffic locking circuit and 45 arranged to supply current to either adjacent section when controlled by current from the other adjacent section whereby under clear traffic conditions the relay at either end of the stretch will become energized when current is supplied to the traffic locking circuit at the other end, a signal 50 at each end of the stretch to govern the movement of traffic into the stretch, and means controlled by the relay at the same end of the stretch for clearing said signal.

8. In combination, a stretch of railway track 55 arranged into track sections each of which is provided with the usual track circuit including a track relay, a traffic locking circuit extending along the stretch arranged into a plurality of different sections with each section including a front 60 contact of each track relay of the track sections adjacent that section of the traffic locking circuit, a source of current and a directional relay at each end of the stretch, manually controlled means at each end to include either the current source or the relay at its end in the traffic locking circuit, repeating means at each junction of adjacent 65 sections of said traffic locking circuit including two directional relays controlled by the traffic locking circuit and arranged to supply current to either adjacent section when controlled by current from the other adjacent section, to thereby 70 carry through under clear traffic conditions of the stretch the influence effected by supplying 75 current to the traffic locking circuit at one end of

the stretch to the relay at the opposite end for energizing that relay, a signal at each end of the stretch to govern the movement of traffic into the stretch, and means controlled by the relay at the same end of the stretch for clearing said signal. 80

9. In combination, a stretch of railway track divided into track sections each of which is provided with the usual track circuit including a track relay, signals located along said stretch and arranged to govern traffic in both directions, a sectionalized line wire for the stretch adapted for use as the common line wire in the control of said signals, a traffic locking circuit for the stretch arranged into a plurality of sections each section of which includes a corresponding section of the sectionalized line wire and a front contact of the track relay of each track section adjacent that section of the traffic locking circuit, means at each end of the stretch adapted to at times supply a control current to the traffic locking circuit, a directional relay at each end of the stretch controlled by the traffic locking circuit, two directional relays at each junction of adjacent sections of the traffic locking circuit controlled by said circuit and arranged to supply current to one adjacent section when controlled by current from the other adjacent section and to supply current to said other adjacent section when controlled by current from said one adjacent section for energizing the relay at the end of the stretch opposite that at which current is supplied to the traffic locking circuit, a signal at each end of the stretch to govern the movement of traffic through the stretch, and means for clearing said signal when the relay at its end of the stretch becomes energized. 95

10. In combination, a stretch of railway track divided into sections, a track circuit including a track relay for each track section, a line circuit 115 for the stretch divided into sections each including front contacts of the track relays of the track sections adjacent such line circuit section, a source of current and a directional relay at each end of each section of the line circuit, manually 120 controlled means at each end of the stretch for selectively including in the section of the line circuit having one end adjacent said means the source of current or directional relay at that end of said section, means at each junction of adjoining sections of the line circuit for including in each of said sections the source of current or 125 directional relay at the adjacent end of such section according as the directional relay at the adjacent end of the other adjoining section is energized or deenergized, a signal at each end of the stretch to govern the movement of traffic through the stretch, and means controlled by the directional relay at the same end for controlling said signal. 130

11. In combination, a stretch of railway track, a signal at each end of the stretch to govern the movement of traffic through the stretch, a line circuit for the stretch, divided into sections, a source of current and a directional relay at each 140 end of each section of said line circuit, a manually controlled relay at each end of the stretch, means at each end of the stretch comprising a front contact of the adjacent manually controlled relay for including in the end section of the line circuit 145 the adjacent directional relay, means at each end of the stretch comprising back contacts of the adjacent manually controlled relay and directional relay and a contact closed when the adjacent signal indicates stop for including in the end section 150

of the line circuit the adjacent source of current, means at each junction of adjoining sections of the line circuit for including in each of said sections the source of current or directional relay at 5 the adjacent end of such section according as the directional relay for the adjacent end of the other adjoining section is energized or deenergized, and means for clearing each signal when the manually controlled relay and the directional relay at the 10 same end of the stretch are energized.

12. In combination, a stretch of railway track, a signal at each end of the stretch to govern the movement of traffic through the stretch, a line circuit for the stretch divided into sections, a

source of current and a directional relay at each end of the stretch, manually controlled means at each end of the stretch for selectively including in the end section of the line circuit adjacent said means its source of current or directional relay, 80 repeating means at each junction of adjoining sections of the line circuit effective to include a source of current in either of said sections at the end adjacent such junction when the other adjoining section is energized at the end remote 85 from such junction, and means controlled by each directional relay for clearing the signal at the same end of the stretch.
